(No Model.)

J. L. BOGERT.

STEAM ENGINE.

No. 325,487.

Patented Sept. 1, 1885.

N. PETERS, Photo-Lithographer, Washington, D. C.

UNITED STATES PATENT OFFICE.

JOHN L. BOGERT, OF FLUSHING, NEW YORK.

STEAM-ENGINE.

SPECIFICATION forming part of Letters Patent No. 325,487, dated September 1, 1885.

Application filed January 31, 1885. (No model.)

To all whom it may concern:

Be it known that I, JOHN L. BOGERT, of Flushing, in the county of Queens and State of New York, have invented an Improvement 5 in Steam-Engines, of which the following is a specification.

This invention is made for inclosing the cranks and crank-shaft of a vertical duplex single-acting engine in such a manner that 10 access can be had for removing the cranks, the connecting-rods, and the plungers whenever required.

In the drawings, Figure 1 is an elevation of the engine endwise of the crank-shaft, and 15 Fig. 2 is a side elevation partially in section. Fig. 3 is a section at the line *xx*, and Fig. 4 is an elevation of one of the hinges of the case.

The cylinders A and B stand vertical. They 20 are preferably cast together, and at C is the hub or flange for receiving the steam-pipe, and at D the similar flange for the exhaust-pipe. The valve is preferably between the cylinders, and made so that one valve serves 25 for the two cylinders, and the piston or plunger of one is made to ascend as the other descends, and the piston and plunger in each cylinder may be made with a wrist-pin, as shown in my Patent No. 309,686.

30 The wrist-pins are shown by dotted lines at *c* and the connecting-rods at *d*.

The peculiar construction of the valve and ports connected therewith does not form any necessary part of the present application.

35 The cranks F G are placed at one hundred and eighty degrees apart, and the crank-shaft H is usually provided with the two driving-pulleys or fly-wheels K K outside its bearings.

I do not in this application describe or claim 40 any peculiarity in the construction of the cranks or of the pitman or connecting-rods.

45 My present invention relates especially to the peculiar construction of the inclosing-case and the parts that support the crank-shaft and engine.

At the lower ends of the cylinders A B are 50 the flanges *a*, and these rest upon and are bolted to the casing L, that is hollow and of a quadrangular form, the sides and ends being somewhat inclined, and cast with the case are the upper portions, *m m n*, of the journal-

boxes of the crank-shaft. The portions *m m* are at the two ends of the case and project principally inwardly, and the center box, *n*, is upon a web or bar, *n'*, that goes across the middle part of the case. The caps *o o o'* are below the respective portions *m m n* and are bolted on. These journal-boxes are usually filled with Babbitt-metal.

It will now be understood that the twin 60 single-acting cylinder-engine before described is complete in itself and could be run if inverted, so as to stand upon the cylinder-heads; but with engines especially that run at high speed it is preferable to place the cranks 6 and shaft as low down as possible, so as to lesson vibration. In providing a support for the engines I at the same time inclose and protect the cranks and parts from dust and injury and provide for lubrication.

The box-shaped base is a casting of the requisite weight and strength, with a bottom, P, ends Q, and front and back, R R'. The case is hinged to this base by the hinges S, which are preferably three in number, one in the 75 middle and one near each end. Each hinge is made of a bolt, 1, passing through the two lugs 2 2, or flanges cast on L, and also through an eye at the upper end of the bolt 3, which eye is between the flanges, and the bolt 3 80 passes through a lug, 4, upon the back R', and is secured by nut 6 below the lug. It is now 85 to be understood that upon these hinges S the whole of the engine can be swung back so as to be laid into a horizontal or nearly horizontal position to give access to the cranks, boxes, shaft, pitmen, or the pistons or plungers, the steam and exhaust pipes being first disconnected or formed with swinging joints.

When the engine is turned up vertically, it 90 rests firmly upon the upper edges of the box-shaped base. It will be seen that the ends Q Q of this base are notched to allow for the reception of the journal-box caps, and the surfaces 7 and 8 are preferably planed off, so 95 as to cause the case L to take a firm bearing upon the box-shaped base.

Adjacent to the planed surfaces the flanges at the top of the base and the bottom of the case are recessed for the reception of a thick strip of felt, *t*, which is compressed by the weight of the engine and serves to effectually

exclude the atmosphere and any dust or foreign substances.

There is a central rib or frame, T , to strengthen the box-shaped base.

5 Whenever the necessary appliances for swinging over the engine are easily provided the same may be availed of; but I usually provide projecting lugs 12 upon the front, R , near the middle, and a swivel joint-piece, 13, 10 between them, through which passes the screw u , and there are similar flanges or lugs, 14, projecting from the case L , and between these is a swiveled nut, 15, for the said screw u .

By rotating the nut within the swivel, or by 15 revolving the screw u , the front edge of the case will be raised and the engine swung back and held at any point to which it may be moved, as indicated by the dotted lines, Fig. 1. The reverse rotation of the screw closes 20 the parts, and clamps them firmly when the surfaces of the case and base come into contact.

There are three oil-cups, V , preferably cast with the front portion of the case L , and 25 through the bottoms of these the feed-tubes 25 (shown by dotted lines in Fig. 1) extend over the journal-boxes m m n , and the discharge of oil through these tubes is regulated by a screw-plug, 26, or a cock. The lubricating 30 material may pass to the respective crank-pins as illustrated in my Patent No. 310,979.

I claim as my invention—

1. The combination, with the twin single-acting steam-cylinders, connecting-rods, cranks,

and shaft, of a case bolted to the ends of the 35 cylinders and provided with the journal-boxes or bearings and a box-shaped base upon which the edges of the case rest, and hinges to connect the case and base, substantially as set forth.

40 2. The combination, with the twin cylinders, connecting-rods, and cranks, of a case connected to the cylinders and provided with journal boxes or bearings, a box-shaped base upon which the lower edges of the case rest, 45 and an intervening strip of elastic material—such as felt—to exclude dust, substantially as set forth.

50 3. The combination, with the engine and the case inclosing the cranks of a box-shaped base, hinges to connect the case and base, and a screw to clamp the parts together, or to swing the case open to give access to the cranks and other parts, substantially as set forth.

55 4. The combination, with the twin upright-cylinder engines, of a case surrounding the cranks, and a box-shaped base upon which the case rests, and oil-holders upon the case for lubricating the bearings of the crank-shaft, substantially as set forth.

Signed by me this 26th day of January, A. D. 1885.

JOHN L. BOGERT.
